APPARATUS FOR TWISTING FILAMENTS,
ETC.William Whitehead, Cumberland, Md., assignor
to Celanese Corporation of America, a corpora-
tion of Delaware

Application May 11, 1932, Serial No. 610,574

1 Claim. (Cl. 117—21)

This invention relates to a novel method of and apparatus for twisting and doubling yarns, straws and threads of fibres and filaments of any kind and especially yarns, straws or threads of cellulose acetate or other artificial silk filaments or fibres.

An object of this invention is to provide a simple process and apparatus for twisting and doubling yarns, straws or threads in an economical and efficient manner.

Another object of my invention is the production of compound yarns, straws or threads having properties which enable them to be submitted to textile and fabrication processes without damage and which impart the necessary qualities of drape, handle, optical requirements and wear in fabrics produced from such compound yarn or threads.

Other objects of this invention will appear from the following detailed description.

In one aspect my invention comprises the doubling together of yarns, straws or threads (hereinafter referred to as threads) to which a twist is imparted with a thread to which no twist is given. In carrying out this feature of my invention, a package of thread which is to receive the twist is mounted on a twisting spindle which is hollow and carries on its head a fier. The thread from the package passes through one arm of the fier, through a thread guide and onto a take-up bobbin. A second thread from a suitable source of supply passes up through the hollow spindle and fier head under a tension just sufficient to straighten the thread but not to strain it. This thread combines with the rapidly rotating thread from the bobbin in the thread guide but no twist is imposed on it, the thread from the bobbin merely wrapping itself around it with the desired number of turns which is controlled by the relationship between the winding up speed of the combined threads and the speed of the twisting bobbin.

Where low twists are desired in the doubling operation, it is not necessary to employ a fier or similar acting device, as the thread from the bobbin balloons freely and combines with the other thread at the thread guide with the desired results. When it is desired to impose high twists, such as are employed for crepe threads which are used in the manufacture of natural or artificial silk crepe fabrics, for example, crepe de chine, crepe marocain, georgette, etc., I have found it preferable to use a fier or similar acting device, such as a ring adapter, which prevents the high twist imposed on the yarn from

running back onto the bobbin irregularly thus forming irregular thread. It is also advantageous to use a fier even when producing thread having a moderately low twist, as this device restricts the width of the balloon formed by the rotating thread thereby permitting of the use of a greater number of spindles in any given space.

A modification of this principle of twisting and doubling simultaneously is the mounting of spindles one above the other and taking the twisted and doubled thread produced by the lower spindle through the hollow spindle of the bobbin above and so on whereby there may be produced doubled threads of similar, opposing or different twists in a single operation. Combining threads of opposite twists is especially beneficial where the twist is high, as in crepe threads where, for example, 50, 60, or more turns per inch might be imposed on 150 denier natural or artificial silk thread, in that the opposing twists tend to set each other and do not require the usual twist setting operation of steaming, sizing, etc. Such threads when employed as warp or weft in a fabric do not display any tendency to curl the fabric in one direction during the processes of dyeing and finishing or subsequent domestic washing as do fabrics made from threads having such a high twist imposed in but one direction. Heretofore threads of such high twists have been inserted in fabrics with alternate ends or alternate numbers of ends of a twist in opposite directions to counteract this tendency to curl the fabric. I have found that the threads produced according to the process of my invention which are not "set" by steaming or other means, have somewhat higher crepeing powers, that is, they produce a better "figure" in finished fabrics than threads in which the twist has been set. Threads produced prior to my invention have been "set" of necessity, since otherwise they are too lively and snarl in subsequent processing. A possible explanation for such difference is that the crepeing or producing of a figure in fabrics of high twist, either in the weft or warp, is due to a torsional force set up in the yarn by the imposition of such high twist and that this residual force is somewhat reduced by steaming or other wetting methods.

A further modification of my invention involves the combining of a stretched thread which contracts on scouring and/or dyeing processing. An example of such thread suitable for such purposes would be an acetone soluble cellulose acetate thread stretched, for example, 8% in length. Such thread, when wetted or treated with swell-

ing agents, contracts approximately to its original length.

By way of describing this feature of my invention, the following example is given.

- 5 150 denier thread composed of an acetone soluble cellulose acetate is fed to the hollow spindle by two feed rollers in succession; the second roller rotating at a speed of 8% greater than the first and the thread so tensioned and wrapped around 10 these two rollers that both act positively or approximately so in respect to the length of yarn they feed per unit time. The thread leaving the second roller passes up through the hollow spindle, through the thread guide and onto the take-up bobbin. The high speed spindle rotates at a speed of approximately 11,000 R. P. M. and on 15 it is mounted a bobbin of thread similar to that being stretched. The unstretched thread from this bobbin combines with the stretched thread 20 at the thread guide as before described. The take-up bobbin is rotated at a low speed so that the twist in the thread from the bobbin and its twist about the stretched thread in which no further twist is imposed, is 55 turns per inch. 25 Such thread employed in crepe fabrics contracts heavily owing to the contraction of the stretched thread back to its original unstrained length and this contraction produces a heavy crepe or figure in the fabric. Obviously I may stretch the 30 thread in a process prior to the twist-combining process.

A highly desirable property of crepe fabrics, the weft or warp of which comprises thread produced according to the process of my invention 35 and which thread combines a high twist and wrapped about an end of moderate or low twist, is that garments produced from such fabrics retain their shape in a much superior manner to crepe fabrics produced according to prior meth- 40 ods. The reason for this is that a crepe thread produced according to methods heretofore employed has the physical form of a spiral or partially pulled out coil spring. Therefore when such crepe threads were incorporated in a garment and said garment was subjected to constant 45 wear or repeated strains, especially under humid conditions, these slight spirals were straightened or stretched thereby deforming the garment. Thread produced according to the process of my 50 invention, however, which comprises one end of moderate or low twist, do not so deform since the thread of moderate or low twist has no such spiral form and is already straight.

Threads produced according to the process of 55 my invention dye more rapidly and thus effect economies in dyeing process. This applies to threads comprising an end of low or moderate twist. The reason for this is that high twist threads because of the residual forces therein 60 resist penetration of wetting-out liquids and dyes. Further the very close accumulation of the filaments in such thread results in the presentation of a very small surface per mass for such adsorption compared with a loose or low twist thread. 65 Wrapping a high twist thread with high twist about a thread of relatively low twist produces a channel by which the liquids and dyes may penetrate into the interior of the high twist threads. This probably explains why such threads wet 70 out and dye more rapidly than threads of similar total denier twisted to the same extent and according to methods heretofore employed.

Another modification of my process involves the application of this twisting principle to the 75 winding up process involved in the spinning and

manufacture of synthetic yarns and the like, wherein thread freshly made is lead from the spinning chamber up through the hollow spindle and another thread previously spun is mounted on a bobbin on twisting spindle.

Stronger crepe threads may be made according to the process of my invention. It is well known that all threads after a certain point, become weaker by added increments of twist. In the process of my invention, where I combine a 10 thread of low twist with a thread which twists around this forming a high twist covering, this loss of strength on account of a high twist, only applies to part of the thread and not to the core of the thread and thus the loss in strength on 15 the total threads is not as great as in other threads.

It will thus be seen that by the process of my invention, there may be produced threads with novel effects, crepe threads of higher tenacity, 20 crepe threads which dye more readily and compound threads in which are combined threads of standard and anti-standard twists, threads of low and high twists, threads of different dyeing characteristics, or of different compositions, or of dif- 25 ferent sizes, or of different lustre and threads which expand or contract on damping or dyeing. In fact, there may be combined threads of any different properties to give potential cross-dyeing or contrasting physical or optical properties. By 30 my invention, all of the foregoing compound threads may be produced efficiently and at low cost. Moreover, fabrics woven from spiral wound threads produced in accordance with my invention have the highly desirable property of being 35 more resistant to "slip" than fabrics woven from other threads or yarns.

In order further to illustrate my invention but without being limited thereto, reference is had to the accompanying drawing, wherein

Figure 1 is an elevation of the device of my invention, partly in section, to show the spindle construction; and

Figure 2 is an elevation showing my invention in an arrangement for producing doubled threads 45 of similar, opposing or different twists in a single operation.

Referring to Figure 1 of the drawing, there is shown a twisting spindle generally indicated by the reference numeral 5 which comprises a hollow spindle 6 formed integral with and which is driven by a whorl 7. The whorl is mounted on anti-friction bearings 8 for rotation relative to a tubular member 9 by which the twisting spindle is fixed to the frame of a twisting machine. 50 A bobbin 11 is mounted on the twisting spindle 5 and a flier 12 is carried on the head of the hollow spindle 6.

Assuming the apparatus to be twisting and doubling, the twisting spindle 5 rotates in an 60 anti-clockwise direction, as viewed from above. The thread 13 from the rotating bobbin passes through one arm of the flier to the thread guide 14. The rotating thread 13 combines with thread 15 which passes up through tubular member 9, 65 hollow spindle 6 and flier 12 and the compound thread is wound on any suitable textile package, such as a take-up bobbin 16. The thread 15 is taken from any suitable textile package, not shown, and is under a moderate tension sufficient 70 to keep it straight but not to strain it. It is to be understood that in this doubling operation, no twist is imposed on the thread 15, the thread 13 being merely wrapped around thread 15 in the desired number of turns.

The degree of twist imparted to the thread or the number of turns per inch placed on the thread 15 by my device is of course governed by the speed of rotation of the bobbin 11 and 5 the rate at which the combined thread is taken up by take-up bobbin 16. By rotating the bobbin 11 at high or very high speeds, e. g. 10,000 to 20,000 or more revolutions per minute, high or 10 very high degrees of twist, e. g. 50, 60 or more turns per square inch, can readily be imparted to the thread. It will be understood that the take-up bobbin 16 will be driven at a much lower circumferential speed than the bobbin 11.

Where high or very high speeds of rotation of 15 the bobbin 11 are employed, as, for instance, in the production of crepe threads, care should be taken that the twisting spindle carrying the bobbin 11 revolving at the high or very high speeds, should be mechanically balanced to a 20 high degree of accuracy.

As pointed out above, it is often desirable to stretch the thread 15 before it is combined with thread 13. To this end I have provided feed rollers 17 and 18 which may be rotated by any suitable means, the roller 17 being adapted to rotate at a speed greater than the speed of roller 18, for example about 8% greater. The thread 15, 25 being fed to the twisting spindle, is wrapped around the rollers 17 and 18 to prevent slipping and is so tensioned that the rollers stretch the 30 thread about 8% in length.

Referring to Figure 2, an arrangement of producing doubled threads of similar, opposing or different twists in one operation is shown. 35 Twisting spindles, generally indicated by the reference numerals 19 and 21, similar to twisting spindle 5, are mounted one above the other. These twisting spindles are also provided with hollow spindles 22 and fliers 23. Thread guides 40 24 and a take-up bobbin 25 are included in the

construction of the apparatus. In the arrangement shown, threads 26 and 27 are combined to form a compound thread 28 similar to the compound thread formed by the device shown in Figure 1, which is led up through the hollow 5 spindle of twisting spindle 19. A thread 29 from the bobbin 31 is twisted about the thread 28 to form the compound thread 32 which is wound on take-up bobbin 25. It will be readily understood that by changing the direction of rotation 10 of bobbin 31 and the speeds of rotation of the bobbins, compound threads having twists which are different in degree and kind may be produced. While I have shown two twisting spindles in Figure 2, it will be readily seen that any required number of twisting spindles may be placed 15 one above the other to produce the desired compound thread.

It will be understood that the foregoing detailed description is given merely by way of 20 illustration, and that many variations may be made therein without departing from the spirit of my invention.

Having described my invention, what I desire to 25 secure by Letters Patent is:

Apparatus for producing compound threads comprising in combination a rotatable spindle forming a support for a thread package said spindle being hollow to provide a passage through which a thread is adapted to pass, means for rotating said spindle, a plurality of rollers positively driven at different speeds for imparting a substantially permanent stretch to said thread and a take-up device, the construction and arrangement being such that the thread after being 30 stretched passes through the hollow spindle and on its way to the take-up device has the thread from said thread package twisted around the same. 35

WILLIAM WHITEHEAD. 40
